FIG. 1

FIG. 2

FIG. 3

FIG. 1 is a front elevational view of a ceiling air deflector frame showing my new design;

FIG. 2 is a cross-sectional view taken through the middle of FIG. 1; and

FIG. 3 is a front perspective view thereof. The rear of the deflector is formed with ridges and grooves or indentations as illustrated in FIG. 2 conforming to the front surface shape of the frame as shown.

I claim:

The ornamental design for a ceiling air deflector frame, as shown and described.
